UNITED STATES PATENT OFFICE

ALBERT V. STEGEMAN, JR., OF FORT THOMAS, KENTUCKY, ASSIGNOR TO THE WADSWORTH WATCH CASE COMPANY, OF DAYTON, KENTUCKY, A CORPORATION OF KENTUCKY

DESIGN FOR A WATCHCASE

Application filed March 11, 1930. Serial No. 34,818. Term of patent 14 years.

To all whom it may concern:

Be it known that I, ALBERT V. STEGEMAN, Jr., a citizen of the United States, residing at Fort Thomas, in the county of Campbell and State of Kentucky, have invented a new, original, and ornamental Design for Watchcases, of which the following is a specification, reference being had to the accompanying drawing, forming part thereof:

Fig. 1 is a face or front view,

Fig. 2 a side view, and

Fig. 3 a perspective view of a watch case embodying my design, the essential features of which are represented by the full lines.

I claim:

The ornamental design for a watch case, substantially as shown.

ALBERT V. STEGEMAN, JR.
